SHANK POCKET FOR SHOES AND METHOD OF USING THE SAME

Filed May 29, 1935

UNITED STATES PATENT OFFICE

2,068,060

SHANK POCKET FOR SHOES AND METHOD
OF USING THE SAMEBlaine E. Matthews, Portsmouth, Ohio, assignor
to Williams Manufacturing Company, Ports-
mouth, Ohio, a corporation of Ohio

Application May 29, 1935, Serial No. 24,091

7 Claims. (Cl. 36—76)

My invention relates to shoes and in particular to an improvement in shank pockets.

It is a particular object of my invention to provide a ready means of anchoring either end 5 of the metal strip constituting the reinforcing associated with a shank pocket.

It is my object to provide a rectangular hole punched in the heel fiber or reinforcing piece into which a metal shank is fitted after the shoe 10 is finished. The punched reinforcing piece is stapled to the insole. The assembled insole is attached to the last and the shoe lasted complete. The metal shank is then inserted.

It is the object of this invention to save in 15 labor and cost in attaching the shank to a shoe by eliminating the use of tacks or adhesives. This results in a smooth bottom surface, allowing a better attachment to the outsole when using the cementing process for that purpose. By covering 20 the end of the shank with the shank fiber, it is prevented from penetrating the outsole while the shoe is worn.

A further advantage is that the pressure of the 25 heel end of the shank is distributed over a larger area of the heel. Another advantage is that the shank can be accurately located. The shank is not in the way of any of the lasting operations.

The particular object of our invention is to 30 insert the shank after the shoe is lasted and at the time just before the sole cementing operation is performed.

Referring to the drawing, Figure 1 is a bottom plan view showing the metal strip insert before the outsole has been applied and before the heel 35 is applied.

Figure 2 is a section on the line 2—2 of Figure 1.

Figure 3 is a section on the line 3—3 of Figure 1.

Referring to the drawing in detail, 1 designates the toe of a shoe and 2 the heel portion thereof. 3 designates the heel and 4 the outsole.

In the practice of using this invention, a heel 45 fiber or reinforcing piece 5 has a rectangular hole or slot 6 cut therefrom. The ends of this piece extend completely across the shoe as at 7 and 8 and beneath these ends is inserted a metal strip 9 shaped to the shank or instep of the shoe. This metal strip has flat side flanges 10 and an ar- 50 cuate central struck-up portion 11 as shown in Figure 3.

The reinforcing piece 5 is stapled at 8a to the insole. The assembled insole is attached to the last and the shoe lasted complete. The metal 55 shank 9 is then inserted in the hole or slot 6, into

which it fits after the shoe is finished. This is just prior to the operations preparatory to the cementing of the outsole 4 to the shoe. The insole is designated 12.

When the metal stiffener or reinforcing shank 5 piece 9 is in position, the flat side edges 10 are in contact with the upper surface of the fiber reinforcing piece 5 adjacent the side edges of the slot 6. The central struck-up portion 11 extends downwardly and outwardly with a part thereof 10 projecting into the slot 6. The extreme forward end of the reinforcing shank piece 9 is bent upwardly (Figure 2) to prevent the extreme end from injuring the outsole; the forward end of the reinforcing shank piece 9 is also beveled to 15 prevent injury to the insole 12. This extreme forward end of the reinforcing shank piece 9 extends forwardly beyond the forward edge of the fiber reinforcing piece 5. The rear end portion of the reinforcing shank portion 9 extends rearwardly 20 of the slot 6 and is secured between the fiber reinforcing piece 5 and the heel portion of the insole 12.

After the shoe is completed (Figure 2), the rear end portion of the reinforcing shank piece 9 is 25 secured between the heel portion of the insole 12 and the reinforcing piece 5, while the greater part of the central struck-up portion 11 is disposed in the slot 6 and secured between the adjacent part of the insole 12 and the opposite part 30 of the outsole, while the extreme forward end portion, extending beyond the fiber reinforcing piece 5, is secured between the insole and the outsole. Thus, substantial contact is had between the upper surface of the reinforcing shank piece 9 35 and the lower surface or insole 12, while a substantial portion of the central upraised portion 11 thereof is disposed in the slot 6 which prevents lateral displacement thereof; the extreme rear end portion of the reinforcing shank piece 9 is 40 disposed between the fiber reinforcing piece 5 (rearwardly of the slot 6) and the insole 12. The extreme forward end portion of the reinforcing shank piece 9 is secured between the insole and the outsole, while the portion to the rear thereof 45 (between the extreme forward end portion and the slot 6) is secured between the fiber reinforcing piece 5 and the insole.

The leather covering or upper of the shoe which is folded over the insole and tacked in position 50 and cemented is designated at 13. A filler between the outsole and the insole between the flange 13 is inserted on the toe portion as at 14.

In the method of manufacturing a shoe according to this invention, the punched reinforc- 55

ing piece 5 is stapled to the insole and the assembled insole is attached to the last and the shoe lasted complete prior to applying the outsole. Then the metal shank insert 9 is inserted 5 in the shank pockets formed by the reinforcing piece in which has been cut the rectangular opening 6. Then the outsole is applied and the heel is applied.

It will be understood that it is desired to comprehend within this invention such modifications 10 as may be necessary to adapt it to varying conditions and uses.

Having thus fully described my invention, what I claim as new and desire to secure by Letters Patent, is:

1. In a shoe, the combination of a shoe upper and insole construction having a reinforcing piece attached to the bottom thereof from heel to the rear of the ball portion, said reinforcing 20 piece having a slot therein, and a metal reinforcing shank piece having the central portion thereof in said slot between the insole and outsole and either end extending beyond the slot, one of said ends being retained between the reinforcing piece and the insole and the other of said ends being retained between the insole and the outsole; and said shank being adapted for insertion between the insole and the attached reinforcing piece.

2. In a shoe, the combination of a shoe upper and insole construction having a reinforcing piece attached to the bottom thereof from heel to the rear of the ball portion, said reinforcing piece having a slot therein, a metal reinforcing shank piece having the ends thereof inserted beneath the reinforcing piece with the central portion thereof in said slot and extending beyond said reinforcing piece at its forward end, and an outsole and heel adapted to cover the bottom of the 40 shoe, said slotted reinforcing strip and the metal reinforcing shank, said shank being adapted for insertion between the insole and the attached reinforcing piece.

3. In a shoe, an insole, a reinforcing strip extending from the heel to the forward end of the shank having a slot therein, a shoe upper lasted thereon, a metal reinforcing strip inserted in the slot formed between the insole and slotted reinforcing strip with the central portion thereof 50 in said slot and one end extending beyond said strip, an outsole, and a heel, said shank being insertable between the insole and the reinforcing piece after they are attached together.

4. A new article of manufacture for reinforcing a shoe comprising a slotted reinforcing piece stapled to an insole and a metal reinforcing member, the center of which is exposed by the slot in the reinforcing piece and one end of which is inserted between the reinforcing piece and the insole at the heel portion and the other end of which is inserted between the forward end of the reinforcing member and the insole with the extremity thereof extending therebeyond and unattached to insole or reinforcing piece. 5

5. In combination, an insole, a shoe upper lasted thereon, a slotted reinforcing piece extending from the heel to the forward end of the insole area, a portion of which is exposed on the bottom of the shoe between the overlapping portions of the shoe lasted on the insole and the reinforcing piece, and a metal reinforcing strip having an arcuate body conforming to the longitudinal configuration of the heel and insole, the forward end of said metal strip being inserted between the insole and reinforcing strip and extending beyond the forward edge thereof, the central portion thereof extending into the slotted portion of said reinforcing piece, and the rear 25 end of the metal strip being inserted between the reinforcing strip and the insole in the area of the heel and unattached to insole or reinforcing piece.

6. In a method of shoe manufacture, the sequence of steps of (a) securing a longitudinally slotted coextensive reinforcing piece to the heel portion of a shoe insole, (b) lasting the shoe upper and the assembled insole, (c) inserting between the lasted insole and reinforcing piece a shank having a projecting portion complementary to the slot in the reinforcing piece and guiding said shank by the cooperation of said projecting portion and said slot, and (d) attaching 35 the outsole. 40

7. The method of attaching a reinforcing shank having a struck up portion in a shoe comprising (a) stapling a longitudinally slotted coextensive reinforcing piece to the heel portion of an insole, (b) lasting the assembled insole, and (c) 45 inserting the shank between the insole and the attached reinforcing piece with the struck up portion in the slot in the reinforcing piece and guiding said shank by the cooperation of said struck up portion and said slot. 50
